CARL E. H. COLLIANDER, OF PROVIDENCE, RHODE ISLAND, ASSIGNOR TO MARTIN-COPELAND COMPANY, OF PROVIDENCE, RHODE ISLAND.

EYEGLASS CONSTRUCTION.

1,193,518.

Specification of Letters Patent.

Patented Aug. 8, 1916.

Application filed July 2, 1915. Serial No. 37,653.

To all whom it may concern:

Be it known that I, CARL E. H. COLLIANDER, a citizen of the United States, and residing at Providence, in the county of

5 Providence and State of Rhode Island, have invented a new and Improved Eyeglass Construction, of which the following specification is a full disclosure.

This invention relates to eyeglasses and 10 an art of making portions of the same.

One of the objects thereof is to provide a device of the above nature of increased simplicity and durability of construction.

Another object is to provide an eyeglass 15 construction of inexpensive manufacture and attractive appearance.

Another object is to provide in connection with eyeglasses, the lenses of which are 20 slidably connected, means for economizing the use of material and simplifying the construction of the connecting parts.

Another object is to provide a practical art whereby devices of the above nature may be readily made.

25 Other objects will be in part obvious and in part pointed out hereinafter.

The invention accordingly consists in the features of construction, combinations of elements, arrangement of parts and in the 30 several steps and relation and order of such steps, all as will be exemplified in the following description and the scope of the application of which will be indicated in the appended claims.

35 In the accompanying drawings, in which is shown one or more of various possible embodiments of the mechanical features of this invention, Figure 1 is a rear elevation of a pair of eyeglasses. Fig. 2 is a plan of a portion of the same. Fig. 3 is a detailed 40 sectional view taken along the line A—A of Fig. 1, showing the parts on an enlarged scale. Fig. 4 is a detailed sectional view taken substantially along the line B—B of Fig. 2. Fig. 5 is a plan of a piece of tubing. Fig. 6 is a similar view, showing the part 45 bent to a certain form. Fig. 7 is a similar view showing the part at a later stage. Fig. 8 is a similar view of this part mounted in 50 position.

Similar reference characters refer to similar parts throughout the several views of the drawings.

Referring now to Fig. 1 of the drawings, 55 there is shown a pair of eyeglasses of the

type in which the lenses are relatively separable by sliding connection, but it is to be understood that certain of the broader features of this invention are susceptible of embodiment in eyeglasses of other forms 60 and that the term "eyeglasses" is used in a broad sense to denote any device adapted to support lenses upon the face of the wearer. In these glasses, the lenses 1 are supported within rims 2 of the ordinary channel cross-section having inwardly directed flanges. Mounted upon the glasses are any suitable form of nose-guards 3, the particular form here shown comprising a pivot wire 4 soldered to the rim downwardly and rearwardly to provide a bearing surface for the 65 sleeve 5 on the nose-guard. The end of the wire is bent, as indicated at 6, and retains the nose-guard in position as well as limits its swinging movement by engagement with 70 its rear surface, thus allowing a free but limited rocking movement thereon.

Connected with the upper surface of each of the rims 2, as by means of solder, is a tube 7 which is cut apart at 8 at a point 80 substantially in alinement with the joint 8^a between the ends of the otherwise continuous rims. One of the members 7, as hereinafter described, is provided with a flattened extension 9 of semi-elliptical cross-section as shown in Fig. 3 of the drawings. In like manner, the member 7 upon the opposite rim is provided with a flattened extension 10 which bears against the lower surface of the extension 9. The part 9 terminates in and is secured to a sleeve 11 extending about the part 10 and the latter part has secured to its ends a sleeve 12 which holds it in sliding relation to the part 9. A coiled spring 13 compressed between the 95 sleeves 11 and 12 tends normally to urge these apart and draw the members 9 and 10 into fully overlapped position.

Considering, now, the preferred method of making certain portions of the above device, the tube shown in Fig. 5 of the drawings, of suitable length, outer diameter and thickness, is first preferably bent to provide the offset portion 14. The portion 9, as shown in Fig. 7, is thereupon collapsed by 100 a suitable die, preferably to give a semi-elliptical cross-section with a flattened bearing surface. The walls of the tube being of suitable thickness, a resultant cross-section of this flattened portion may be readily 105 110

achieved without cutting away any material and, moreover, the hollow construction of the tube facilitates this last operation. The offset portion 14, which, being tubular, is of a high degree of stiffness relatively to the metal employed, is then secured, as by soldering to the desired portion of the rim 2 as shown in Fig. 8 of the drawings. With the parts so positioned, the tube and continuous rim are sawed apart at the point indicated at 8 in Fig. 8 of the drawings. The inner walls of the tube are then tapped at 15 and a screw 16 passed through the severed tube portion and into operative relation with the threaded part 15.

In the use of the device, the lenses are drawn apart in the manner common with eyeglasses of this type when they are placed in position, and upon release a spring 13 slides the overlapping portions 9 and 10 to bring the rocking nose-guards 3 firmly against the nose. When it is desired to insert or change the lenses, the screw 16 is partially or entirely withdrawn, permitting the lens to be snapped within the rim, and the screw is then tightened, securely holding the rim in position. This arrangement gives what is virtually an increased length of connection between the bar and the lens support, for the severed portion 17 of the tube virtually becomes a part of the bridge when the screw 16 is driven home. Moreover, by this arrangement, the necessity for a separate joint in the rims with separate connecting devices is avoided, and the employment of a tubular member, aside from its other advantages, affords a secure and readily utilized hold for the screw.

The mounting of the nose pad is also simple and reliable, and various other advantages in the matter of simplicity and strength of construction as well as attractiveness of appearance will be obvious.

It will thus be seen that there is provided a device and an art in which the objects of this invention are achieved.

As various possible embodiments might be made of the above mechanical invention and as the above described art might be varied as to the precise manner in which it is carried on, it is to be understood that all matter hereinabove set forth or shown in the accompanying drawings is to be interpreted as illustrative and not in a limiting sense.

Having thus revealed this invention, I claim as new and desire to secure the fol-

lowing combinations of elements, or equivalents thereof, by Letters Patent of the United States:—

1. In eyeglass construction, in combination, a rim, a tubular bridging member having an uncollapsed portion secured to said rim and a collapsed portion extending toward the opposite glass, whereby there is attained a bridging portion of substantially solid and relatively flattened form, said tubular portion and said rim being cut through at substantially registering points, and means securing the portions of said tubular member one to another.

2. In eyeglass construction, in combination, a pair of lens supports, a pair of tubular members each of which has a portion secured to one of said lens supports and a collapsed portion overlapping a similar portion of the other, and means holding said overlapped portions in slidable relation one to the other.

3. In eyeglass construction, in combination, a pair of lens supports, a pair of tubular members each of which has a portion secured to one of said lens supports and a collapsed portion overlapping a similar portion of the other, means holding said overlapped portions in slidable relation one to the other, said tubular members and the portions of the rims to which they are secured being severed at substantially registering points, and means releasably securing the severed portions of said bars to the parts from which they are cut.

4. In eyeglass construction, in combination, a pair of rims, a pair of tubular members the end portions of which are respectively connected with the upper portions of said rims, each of said tubular members having a collapsed portion overlapping the corresponding part of the other, means holding said overlapping parts in relatively slidable relation, each of said rims and the portions of said bars mounted thereon being severed at substantially registering portions, and a pair of screws respectively connecting the severed portions of said bars to the portions from which they are cut.

In witness whereof, I hereunto subscribe my name, as attested by the two subscribing witnesses.

CARL E. H. COLLIANDER.
